UNITED STATES PATENT OFFICE.

CLAUDE E. FURGASON, OF LANSING, MICHIGAN, ASSIGNOR TO REO MOTOR CAR COMPANY, OF LANSING, MICHIGAN, A CORPORATION OF MICHIGAN.

SPARK-CONTROL MECHANISM FOR INTERNAL-COMBUSTION ENGINES.

Application filed December 13, 1926. Serial No. 154,626.

This invention relates to spark control mechanism for internal combustion engines and more particularly to a spark control mechanism which automatically adjusts the spark to obtain correct ignition at all speeds of the motor and under the varying conditions of load upon the engine.

This invention relates to the type of apparatus described and claimed in my copending application, Serial No. 96,904 filed March 23, 1926 but contemplates certain improvements in this prior construction tending to simplify the structure, render the same more compact and thus cheapen the cost of manufacture and facilitate the assembly.

Automatic control of the timing of the ignition for internal combustion engines has recently been adopted more or less universally by the manufacturers of motor vehicles but in most instances such so-called automatic spark control mechanisms have not proven to be fully automatic as they do not provide for a correction of the time of ignition according to all conditions of motor operation. As a consequence the majority of the alleged "full automatic" spark controlling mechanisms have proven inefficient in actual practice. As a result of this many motor vehicle manufacturers are equipping their motors with the so-called "semi-automatic" ignition controlling means as a compromise between the old manual control spark and the "full automatic" spark control. With the semi-automatic spark control the spark is controlled by means of a governor operated in accordance with the speed of the motor whereby as the speed increases the spark is advanced. Under ordinary circumstances this governor control would act satisfactorily if the load conditions imposed upon the motor were at all times uniform. However, inasmuch as they are not the semi-automatic control provides for a further adjustment or correction of the time of ignition by a manual control lever whereby the spark may be retarded when the motor is operating under a heavy load. It is also the practice to retard the spark by this manual control when the motor is started. The skill necessary in order to properly manipulate the manual control lever to properly retard the spark upon an increase in load renders the operation of these semi-automatic spark controls erratic and unsatisfactory as the

operator usually either improperly adjusts the manual control lever or fails to operate the same at all.

As a consequence a full automatic spark control, to be efficient and practical in actual use must provide means, additional to the speed governor control, for additionally adjusting the spark or correcting the same in accordance with load or other conditions and this latter means must be fully automatic and out of the control of the operator.

The governor controlled mechanism for all practical purposes must be so adjusted that it will, under light loads or usual conditions of the motor, cause a relative high advance of the spark. This means that the spark must be originally set slightly advanced in order that the governor may produce the desired high advance of the spark. It has furthermore been found to be impractical in actual practice to cause the governor to take control of the spark before a speed of approximately ten miles per hour has been attained. Therefore, at the outset no automatic control is provided for the spark and furthermore the position of the spark is too far advanced to facilitate the safe and easy starting of the motor. With the semi-automatic control the difficulty of the advanced setting of the spark is overcome in starting by retarding the spark by the manual control lever and as the engine is started this lever is returned to its original position and the spark is then wholly under the control of the governor. Obviously while such an advanced spark is efficient under idling or light loads the sudden loading of the motor and the consequential increase in the supply of fuel thereto will result in a "knocking" or "pinging" which is harmful. On the other hand if the spark is originally set lower so that increases in load upon the motor will not result in the disadvantages just mentioned then the highest efficiency under light load conditions is not obtained.

The efficiency of motors equipped with either semi-automatic or full automatic spark control mechanisms is oftentimes effected by the sluggishness or lack of "pick-up" owing to the inadequacy of the speed control device to quickly advance the spark at the outset. Thus a full automatic spark control mechanism must contemplate means for initially imparting a rapid advance to the spark to thus cause a rapid pick-up from

full idling position and to provide control for the spark between the time of starting and the time at which the governor takes control of the spark. A full automatic 5 spark control must further contemplate means for subsequently correcting the position of the spark in accordance with increases of the load upon the motor by retarding the spark, independently of the adjustment 10 imparted thereto by the governor, and in proportion to the load. As the increase in the amount of fuel fed to the engine cylinders is in direct proportion to the increase of the load upon the motor the 15 means for correcting the spark aforesaid may conveniently be operated by or simultaneously with the fuel throttle.

This invention has therefore as its object 20 to provide means associated with the usual governor control for the spark whereby the time of ignition is positively and automatically additionally adjusted to correct the spark in accordance with conditions to which the governor controlled mechanism is not 25 responsive and to thus provide a spark control mechanism which both theoretically and in actual practice is fully automatic. Another object of the invention is to provide a construction capable of accomplishing 30 the above objects which is simple, compact and which may be manufactured, assembled and operated with facility.

The details of construction of an embodiment of this invention, as well as the objects, and advantages of the invention will 35 be made more apparent as this description proceeds, especially when considered in connection with the accompanying drawings wherein;

40 Figure 1 is a fragmentary side elevational view of a generator and a spark timing mechanism with my invention applied thereto.

Figure 2 is an end elevational view partly 45 in vertical section of the structure illustrated in Figure 1.

Figure 3 is a fragmentary vertical sectional view through the timing mechanism and the distributor head.

50 Figure 4 is a top plan view of the timing mechanism with the distributor head removed.

Figure 5 is a horizontal sectional view taken substantially on the plane indicated 55 by line 5-5 in Figure 1 and

Figures 6 and 7 are fragmentary elevational views showing the adjusting mechanism in different positions.

Referring now particularly to the drawings 60 wherein like reference characters indicate like parts it will be noted there is fragmentarily illustrated a generator 10, the shaft 11 of which is connected by means of a gear 12 to the drive shaft 13 of the spark timing mechanism through the intermediary

of a pinion 14. Shaft 13 extends up through casing 15 and is connected through a centrifugal mechanism indicated generally by the reference character 16 to a timer shaft 17 carrying timer cam 18. While the details 70 of the centrifugal mechanism are immaterial its function is obvious it being a well known means of advancing the timer shaft 17 relative to the driving shaft 13 as the speed of the engine increases. As viewed 75 in Figure 4 the advance of the spark is effected by moving timer shaft 17 and consequently cam 18 in a clock-wise manner.

Cam 18 is adapted to be rotated in a clock-wise direction for oscillating timer 80 lever 19 which is pivotally supported as at 20 to the shell 21. The shell 21 is rotatably mounted on the casing 15 by means of a tubular portion 22 which extends therein. With the timer lever 19 mounted upon the shell 21 it will be obvious that a rotation of 85 this shell will also effect the timing of the ignition as the timer lever will be moved relative to cam 18.

Encircling the tubular extension 22 of shell 21 is a collar 23 in the form of a split ring the ends of which are united by a bolt or set screw 24 whereby the same may be assembled and clamped into engagement with this tubular extension 22. The collar 23 is provided with a substantially horizontally extending arm 25 having a graduated segmental portion 26, the graduations of which cooperate with a fixed mark on the shell so that the collar may be rotatively adjusted relative to the shell and the extent or position of the adjustment indicated by the 90 graduations on the segments.

The collar 23 is also provided with a vertically arranged downwardly extending arm 105 or abutment 27 which may be recessed on one side thereof to provide a bracket or seat for a spring 28 which bears with its other end against an abutment 29 projecting from casing 15. The purpose of spring 28 is to 110 normally urge shell 21 toward the left as seen in Figure 1.

Pivoted on the casing 15 as at 30 is a lever 31. This lever is provided with an extension or lip 32 which engages extension 27 on collar 23 on the side thereof opposed to spring 28. The purpose of this lever is to cause a rotation of shell 21. Pivoted as at 33 is an operating lever 34 adapted to be operated by or simultaneously with the fuel throttle of the engine. For this purpose this lever may be connected by means of a link 35 to a throttle control lever 36 mounted on throttle control rod 37. The reference character 38 indicates a throttle pedal lever and 39 the throttle pedal. As the throttle pedal 39 is depressed lever 34 will be swung to the right as viewed in Figure 1.

The lever 34 carries a roller 40 which is 130

adapted to engage the adjacent edge of lever 31 which is shaped to form a cam surface designed with particular reference to the requirements of the engine as well as the 5 spark timing. A comparison of Figures 1, 6 and 7 will indicate more readily three of the positions to which the lever 31 is adjusted by reason of the engagement of the roller 40 of lever 34 with this cam surface. 10 As shown in Figure 1 the roller 40 in one of the extreme positions of the levers reposes in recess 41 and for the purpose of preventing accidental disengagement of the roller with the cam surface the end of lever 15 31 may be extended to form a hook-shaped stop 42. During the first movement of lever 34 to the right, roller 40 engages the crest of cam 43 and thus moves lever 31 to the right which causes a movement of shell 21 in the 20 direction of arrow A, see Figure 1, or in a counterclock-wise direction which results in a rapid advance of the spark. The roller 40 then engages the cam surface 44 and owing to the configuration of the same the 25 direction of movement of lever 31 is reversed so that during the continued movement of lever 34 toward the right lever 31, under the influence of spring 28, moves toward the left thus permitting a movement of shell 21 in a direction opposite to that of arrow A or in a clock-wise direction which effects a retarding of the spark. The depth 30 of cam recess 41 is such that the spark is normally held in a sufficiently retarded position to permit the ready starting of the 35 motor. This position of the spark is also suitable for the motor under full idling, no load condition. However, immediately upon any movement of the lever 34, which 40 would be the result of any depression of throttle pedal 39, roller 40 starts to move up the side of cam recess 41 to the cam crest 43 and this causes a rapid displacement of lever 31 to the right and as a consequence a rapid 45 advance of the spark. This provides the desired "kick-off" or initial acceleration of the motor and steps up the position of the spark from the full retarded position suitable for starting to a position where the 50 spark is advanced sufficiently for the highest efficiency of operation. This position of the levers is illustrated in Figure 6 and under light load conditions the levers will remain more or less in this position. However, 55 as the load upon the motor increases and it becomes necessary to open the throttle further to supply more fuel to the engine cylinders the lever 34 will be moved further toward the right toward or into the position 60 illustrated in Figure 7 wherein the roller 40 is in engagement with the cam surface 44 which permits a movement of lever 31 toward the left or in a direction opposite to the movement of lever 34. This 65 movement of lever 31 permits spring 28 to move shell 21 toward the left or in a clockwise direction which retards the spark, it being readily apparent that the amount the spark is retarded increases simultaneously with and in proportion to the increase in 70 load as determined by the further opening of the throttle. As pressure upon the throttle pedal 39 is released the lever 34 will return to its position illustrated in Figures 6 or 1 and the movements of the lever 31 will 75 be inversely to those just described.

It will be apparent from the foregoing description that the advantages outlined hereinbefore are obtainable with the herein described construction and that a control 80 mechanism which is fully automatic is produced. It will be understood that the adjustments imparted to the spark timer mechanism are in addition to and independent of the adjustment resulting from 85 the centrifugal device 16. In fact the centrifugal device adjusts the time of ignition through the cam 18 while the mechanism controlled by the throttle adjusts the timer lever 19. 90

Obviously changes may be made in the specific construction herein described without departing from the spirit and scope of this invention and to this end reservation 95 is made to make such changes as may come within the purview of the accompanying claims.

What I claim as my invention is:—

1. In an internal combustion engine, means for timing the ignition including two movable parts, a speed governor controlling one of said parts and a cam member controlling the other in accordance with the position of the fuel throttle of the engine to first advance and then retard the same, whereby the time of ignition is determined by the combined effort of the speed of the engine and the load thereon. 100
2. The combination with a governor controlled spark timing mechanism and a throttle for internal combustion engines, of a single control means operable by said throttle and acting to initially impart an advance to said spark timing mechanism and to subsequently retard said mechanism in proportion to the extent said throttle is opened. 110
3. The combination with a speed governor controlled spark timing mechanism and a fuel throttle for an internal combustion engine, of means for additionally adjusting said timing mechanism including a cam member operated by said throttle and designed to initially advance said timing mechanism and subsequently retard the same in proportion to the opening of the throttle. 120
4. The combination with a speed governor controlled spark timing mechanism and a fuel throttle for an internal combustion en- 125

gine, of means for additionally adjusting said timing mechanism including a cam member operated by said throttle and designed to permit a full retardation, initially 5 advance said timing mechanism and subsequently relatively retard the same in proportion to the opening of the throttle.

5. The combination with a spark timing mechanism including a movable part and a 10 throttle for an internal combustion engine, of adjusting mechanism for said timing mechanism comprising, a lever actuated by said throttle and a second lever operated thereby for adjusting said movable part, 15 said second lever being provided with a cam surface engaged by said first lever, said cam surface including a recess permitting full

retardation, a crest portion to cause an initial advance and a portion causing a limited retardation of the spark.

6. The combination with a spark timing mechanism including a movable part and a throttle for an internal combustion engine, of adjusting mechanism comprising, a lever actuated by said throttle and a second lever 20 operated thereby for adjusting said movable part, said second lever being provided with a cam surface engaged by said first lever and so shaped that a movement of said first lever in one direction effects a 25 movement of said second lever in both directions.

In testimony whereof I affix my signature.
CLAUDE E. FURGASON.
